WITNESS:

UNITED STATES PATENT OFFICE.

JAMES SAMETZ, OF NEW YORK, N. Y.

PROPELLER SCREW.

Application filed January 24, 1922. Serial No. 531,421.

To all whom it may concern:

Be it known that I, JAMES SAMETZ, a subject of the King of Italy, residing at New York, in the county of New York and State 5 of New York, have invented new and useful Improvements in Propeller Screws, of which the following is a specification.

This invention comprehends the provision of a propeller wherein the blades are 10 elongated horizontally to increase their effective working areas, and connected to the hub by spokes or the like, thereby eliminating the resistance usually offered by that portion of continuous blades adjacent the 15 hub, which have little or no working value.

The nature and advantages of the invention will be better understood when the following detailed description is read in connection with the accompanying drawing, the 20 invention residing in the construction, combination, and arrangement of parts as claimed.

In the drawing forming part of this application, like numerals of reference indicate 25 similar parts in the several views, and wherein:

Figure 1 is a plan view of the propeller.

Figure 2 is a side elevation.

Referring to the drawing in detail, 10 indicates the hub of the propeller and 11 the blades thereof. As illustrated, each blade is elongated horizontally to increase its effective working area, each blade being twisted

as shown, while the blades at the opposite sides of the hub are oppositely disposed in 35 the usual manner. In contra-distinction to the blades being continued to the hub and indirectly through the medium of spokes or the like 12, thereby providing a space between the hub and the adjacent edges of the 40 blades which eliminates the resistance usually offered by that portion of continuous propeller blades adjacent the hub, and which portion of said blades in reality does not add to the efficiency of the working area of the 45 blades.

While it is believed that the nature and advantages of the invention will be readily apparent, I desire to have it understood that I do not limit myself to what is herein shown 50 and described, and that such changes may be resorted to when desired as fall within the scope of what is claimed.

What I claim is:—

A propeller comprising a hub, spaced pairs 55 of spokes radiating therefrom and arranged at diametrically opposite sides of the hub, the spokes of each pair being diametrically disposed with relation to the hub, a blade supported by each pair of spokes and each 60 blade being elongated horizontally and twisted longitudinally, with the blades extending in relatively opposite directions.

In testimony whereof I affix my signature.

JAMES SAMETZ.
